UNITED STATES PATENT OFFICE.

JOSEPH W. BRENKERT, OF SAN DIEGO, CALIFORNIA.

DRINKING-FOUNTAIN.

1,273,322.

Specification of Letters Patent. Patented July 23, 1918.

Application filed May 2, 1917. Serial No. 165,869.

To all whom it may concern:

Be it known that I, JOSEPH W. BRENKERT, a citizen of the United States, residing at San Diego, in the county of San Diego and State of California, have invented certain new and useful Improvements in Drinking-Fountains, of which the following is a specification.

My invention relates to drinking fountains usually used in public places for drinking purposes, and the objects of my invention are: first, to provide a drinking fountain of this class which is highly sanitary, the opening being closed by gravity when the water pressure is off, thus preventing dust and dirt from entering; second, to provide a fountain of this class in which the quantity of water may be readily regulated so as to provide for places where there is different water pressure; third, to provide a fountain of this class in which the principal parts of said fountain may be readily taken apart and sterilized or cleansed; fourth, to provide a fountain of this class which is very simple and economical of construction, durable, easy to operate, easy to repair and will not readily deteriorate or get out of order.

With these and other objects in view as will appear hereinafter, my invention consists of certain novel features of construction, combination and arrangement of parts as will be hereinafter described in detail and particularly set forth in the appended claims, reference being had to the accompanying drawings and to the characters of reference thereon which form a part of this specification in which:

Figure 1 is a top view of my drinking fountain. Fig. 2 is a longitudinal sectional view minus the control valve and showing parts in elevation to facilitate the illustration, and showing the fountain closed. Fig. 3 is a similar view showing the fountain open and showing a control valve in the supply pipe line. Fig. 4 is a top view of the spider for regulating the movement of the regulating valve.

Similar characters of reference refer to similar parts throughout the several views.

The cylindrical member 1, sleeve 2, regulating valve 3, spider 4, control valve 5 and supply pipe 6 constitute the principal parts of my drinking fountain.

The cylindrical member 1 is provided with a semi-spherical head provided with a

hole 1^a in the center thereof adapted for an outlet for the water, and mounted so as to fit snugly therein is the sleeve 2 which is provided with beveled ends 2^a and 2^b, the beveled end 2^a forming a seat for the regulating valve 3, and the beveled end 2^b serving as a stop for the spider 4. This cylindrical member 1 is threaded internally at its open end at 1^b adapted to fit on the end 65 of the supply pipe 6 and be secured thereon by said thread 1^b. This supply pipe 6 is provided at any desirable place in the line adjacent the fountain with a control valve 5 which may be any conventional valve for controlling the flow of water to said fountain. The regulating valve 3 is a tapered valve adapted to fit the bevel 2^a and is of suitable diameter to permit a good supply of water to pass around the same as shown 70 in Fig. 3 of the drawings when it is raised up by pressure of the water as shown in Fig. 3. It is provided with a stem 3^a which extends down and through the hole 2^c in the sleeve 2, and it is threaded at its lower end, 80 and on this threaded end is screwed the spider 4 which is provided with a central hole 4^a threaded to conform to the thread on the end of the valve stem 3^a. The upper and outer ends 4^b of the arms 4^b are beveled 85 conforming to the bevels 2^b on the lower end of the sleeve 2 so that the spider may be screwed onto the valve stem 3^a a suitable distance, and provides for adjustment of the movement of the valve 3 for regulating the 90 quantity of water through the outlet of said drinking fountain in accordance with the water pressure.

Though I have shown and described a particular construction, combination and arrangement of parts, I do not wish to be limited to this particular construction, combination and arrangement but desire to include in the purview of my invention the construction, combination and arrangement 100 substantially as set forth in the appended claims.

It is obvious that with this construction there is provided a drinking fountain in which the quantity of water may be readily 105 regulated and adjusted, that when the pressure is closed by the control valve the regulating valve will close the opening, preventing dirt, dust and other unsanitary things from entering said fountain, that when the 110 pressure is on the valve is raised by the water pressure permitting the water to pass

out in certain regulated quantities regulated by the position of the spider 4 on the valve stem 3^a, that the device is simple and economical of construction, durable, easy to 5 operate, will not readily deteriorate or get out of order, and is sanitary.

Having thus described my invention, what I claim as new and desire to secure by Letters Patent is:

- 10 1. In a drinking fountain, the combination of a cylindrical member provided with a semi-spherical end integral therewith and with a hole centrally therein, a water supply pipe upon which the open end of said member is screwed, a sleeve fitted snugly in said cylindrical member provided with tapering ends, a valve adapted to seat on one of said tapering ends, a spider adjustably mounted on the stem of said valve adapted to rest 15 against the other tapering end of said sleeve when said valve is in certain position, and a control valve in said supply pipe whereby said valve will reciprocate in said sleeve with the opening and closing of said control 20 valve.
- 25 2. In a drinking fountain, the combination of a cylindrical member provided with a closed end and an open end and provided with a hole centrally in said closed end, a sleeve fitted into said cylindrical member, a valve seating on the upper end of said sleeve, and means for regulating the movement of said valve adjustably mounted on the stem thereof.
- 30 3. In a drinking fountain, the combination of a cylindrical member provided with 35

a closed end and an open end and provided with a hole centrally in said closed end, a sleeve fitted into said cylindrical member, a valve seating on the upper end of said sleeve, means for regulating the movement of said valve adjustably mounted on the stem thereof, and means for controlling the flow of water to said valve.

4. In a drinking fountain, the combination of a mouth-engaging member provided with a hole in the one end thereof, a sleeve fitted snugly in said mouth-engaging member provided with a beveled end forming a valve seat, a valve adapted to engage said seat, a valve stem extending from said valve through said sleeve, means adjustably mounted on the extended end of said valve stem adapted to regulate the movement of said valve relatively to said sleeve.

5. In a drinking fountain, the combination of a mouth-engaging member provided with a hole in the one end thereof, a sleeve fitted snugly in said mouth-engaging member provided with a beveled end forming a valve seat, a valve adapted to engage said seat, a valve stem extending from said valve through said sleeve, means adjustably mounted on the extended end of said valve stem adapted to regulate the movement of said valve relatively to said sleeve, and means for controlling the flow of water to said mouth-engaging member.

In testimony whereof, I have hereunto set my hand at San Diego, California, this 25th day of April, 1917.

JOSEPH W. BRENKERT.
